UNITED STATES PATENT OFFICE

2,513,846

TOWEL HOLDER

David H. Collins, Grass Valley, Calif.

Application October 2, 1946, Serial No. 700,657

4 Claims. (Cl. 248—314)

1

This invention relates to new and useful improvements in towel holders and more particularly to a device which can easily and quickly be attached to a supporting structure and affords a means for securely holding a towel or the like, merely by inserting a corner of a towel inwardly of said device.

Another important feature of this invention is to provide a device of this character which occupies little space and is neat and attractive in appearance.

A further important feature of this invention is to provide a device of the character referred to that is efficient and reliable in operation, relatively cheap to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of the invention.

Figure 2 is a transverse sectional view thereof taken on a line 2—2 of Figure 1.

Figure 3 is a rear elevational view of the invention, and

Figure 4 is a rear elevational view of the channel-shaped retaining ring.

Referring now to the drawings in detail, wherein, for the purpose of illustration, I have disclosed a preferred embodiment of the invention the numeral 5 represents a metal case having window openings 6 in the sides thereof for the ventilation of said case.

The rear edge 7 of said case is provided with a suitable number of outwardly extending apertured tongues 8 for attaching said case to a supporting structure.

The forward face of said case is provided with an annular opening 9, the edges of said opening extending inwardly to form a recess 11 and with the inner edge of the recess bent to form a radially inwardly extending flange 12.

Punched in flange 12 are a suitable number of slots 13 said slots adapted to receive the tongues 14 formed on the outer circumferential edge 15 of a channel shaped retaining ring 16, said tongues being bent inwardly against the inner surface of flange 12 after insertion in said slots so that ring 16 will be held tightly in recess 11 as shown in Figure 2.

Held in ring 16 so that the inner circumferen-

2

tial edges 17 of said ring 16 bear against its outer surfaces is a circular rubber disc 18 having three slits 19 which radiate outwardly from a central opening 20 as shown in Figure 1.

In use, the device is secured to a wall or like surface and when it is desired to suspend a towel from said device, one end portion of the towel 21 is pushed into disc 18 which deforms due to its slitted portion and grips the inserted end portion 10 of the towel. By merely pulling the towel outwardly said towel is removed from the disc.

The ends of the slits 19 are formed with circular openings 22 to prevent ripping of the material.

15 In view of the foregoing description taken in conjunction with the accompanying drawings it is believed that a clear understanding of the construction, operation and advantages of the device will be quite apparent to those skilled in this art. A more detailed description is accordingly deemed unnecessary.

20 It is to be understood, however, that even though there is herein shown and described a preferred embodiment of the invention the same is susceptible to certain changes fully comprehended by the spirit of the invention as herein described and the scope of the appended claims.

What I claim:

1. A towel holder comprising a case, means carried by the case for securing the same to a supporting structure, said case having an annular recess in its front surface, said recess including an inner flat wall having a central opening, a retaining ring secured in said recess, and a rubber disc secured in said recess by said retaining ring and having a slit therein adapted to receive the corner of a towel.

2. A towel holder comprising a case, means carried by the case for securing the same to a supporting structure, said case having an annular recess in its front surface and having a central opening, an internal flange at the edges of said opening and having slots therein, a retaining ring positioned in said recess, bendable tongues on the retaining ring engaged in the slots behind the flange, and a rubber disc clamped between the flange and the retaining ring and having a slit therein to receive the corner of a towel.

3. A towel holder comprising a case, means carried by the case for securing the same to a supporting structure, said case having an annular recess in its front surface and having a central opening, an internal flange at the edges 45 of said opening and having slots therein, a chan-

55

nel shaped retaining ring positioned in said recess, bendable tongues on the outer edge of the ring engaged in said slots behind the flange, and a rubber disc clamped between the flange and the inner edge of the ring, said disc having a slit therein to receive the corner of a towel.

4. The combination of claim 3 wherein said case is provided with a plurality of circumferentially spaced air vents.
